Primary Examiner — Jack Reickel

(57) **CLAIM**

The ornamental design for a display screen with animated graphical user interface, as shown and described.

DESCRIPTION

1. Display screen with animated graphical user interface

1.1 : First front view

1.2 : Second front view in changed state

1.3 : Third front view in changed state

1.4 : Fourth front view in changed state

1.5 : Fifth front view in changed state

1.6 : Sixth front view in changed state

1.7 : Seventh front view in changed state

1.8 : Eighth front view in changed state

1.9 : Ninth front view in changed state

1.10 : Tenth front view in changed state

1.11 : Eleventh front view in changed state

1.12 : Twelfth front view in changed state

1.13 : Thirteenth front view in changed state

1.14 : Fourteenth front view in changed state

1.15 : Fifteenth front view in changed state

1.16 : Sixteenth front view in changed state

1.17 : Seventeenth front view in changed state

1.18 : Eighteenth front view in changed state

1.19 : Nineteenth front view in changed state

1.20 : Twentieth front view in changed state

The broken lines showing a display screen illustrate portions of the article that form no part of the claimed design; the appearance of the transitional image sequentially transitions between the images shown in reproductions 1.1-1.20; the process or period in which one image transitions to another image forms no part of the claimed design.

1 Claim, 20 Drawing Sheets
